UNITED STATES PATENT OFFICE.

BENJAMIN SILVERMAN, OF CHATTANOOGA, TENNESSEE, ASSIGNOR OF ONE-HALF TO
J. RUSSEL EARP, OF CHATTANOOGA, TENNESSEE.

METAL LAMP CHIMNEY.

Application filed November 7, 1923. Serial No. 673,259.

To all whom it may concern:

Be it known that I, BENJAMIN SILVERMAN, a citizen of the United States, residing at Chattanooga, in the county of Hamilton and 5 State of Tennessee, have invented certain new and useful Improvements in Metal Lamp Chimneys, of which the following is a specification.

This invention relates to heating devices, 10 and has special reference to a heater for hair treating combs.

More particularly the invention relates to a comb heating attachment for lamps.

One important object of the invention is 15 to provide an improved and simplified general construction of such heater which may be substituted for the ordinary chimney commonly used with oil lamps without change being made in the lamp.

20 A second important object of the invention is to provide an improved form of such heater having a novel arrangement of supporting means for a hair treating comb.

With the above and other objects in view 25 as will be hereinafter apparent, the invention consists in general of certain novel details of construction and combinations of parts hereinafter more fully described, illustrated in the accompanying drawings and specifically claimed.

In the accompanying drawings, like characters of reference indicate like parts in the several views, and:

Fig. 1 is a side elevation of the improved 35 heater applied to a lamp.

Fig. 2 is a view of the heater removed from the lamp and at right angles to Fig. 1.

Fig. 3 is a plan view of the heater showing a comb in position thereon in dotted outline.

40 In the form of the invention here illustrated, there is shown a heater comprising a tubular body member 10 having a lower end 11 cylindrical in form and provided with an upper end 12 of rectangular shape, the 45 body merging gradually from one form to

the other. This lower end is adapted to fit within the crown fingers 13 of the ordinary oil lamp 14.

At each end wall of the rectangular upper end there is provided a notch 15 and extending across said upper end between the side walls are comb supporting rods 16 so arranged that the teeth of the comb may be supported in horizontal position, as shown in Fig. 3, the notches serving to receive and 55 support the comb back.

Below the position of the comb is a series of vent openings 17 so arranged that placing of the comb in position for heating will not cause smoking.

60 For convenience in manipulating the device a handle 18 is secured to one side of the body.

In use the device is simply applied to an oil lamp after the ordinary glass chimney 65 has been removed. The comb is then placed in position and allowed to remain as long as desired.

There has thus been provided a very simple and efficient device of the kind described 70 and for the purpose specified.

Having thus described the invention, what is claimed as new, is:

A heater for the purpose described comprising a tubular member circular in cross 75 section at its lower end and of elongated rectangular form at its upper end, said lower end being adapted to fit within the crown of a lamp, the upper end being provided in each end wall with a notch, said notches being alined and adjacent one side wall of said upper end, and cross bars extending 80 across the upper end between the side walls and adjacent the end walls, said cross bars lying substantially in the plane of the bottoms of said notches, said upper end further having vent openings beneath said cross bar.

85 In testimony whereof I affix my signature.

BENJAMIN SILVERMAN.
